UNITED STATES PATENT OFFICE.

EDWARD M. HEWLETT AND WALDO W. WILLARD, OF SCHENECTADY, NEW YORK, AS
SIGNORS TO GENERAL ELECTRIC COMPANY, A CORPORATION OF NEW YORK.

MEANS FOR REPRODUCING RELATIVE ANGULAR MOTION.

Application filed January 4, 1922, Serial No. 527,012.

This invention relates to means for reproducing relative angular motion and has for its object the provision of improved means for reproducing the relative movements of a plurality of objects.

More specifically our invention relates to means for driving an object differentially in response to movements of two controlling objects with relation to each other so that 10 the driven object is caused to take up a position corresponding to the relative positions of the controlling objects. Although it has various applications, whether the movement of the objects be that of translation or rotation, our invention is particularly applicable 15 to the control of indicators in response to relative movements of two objects, such as telescopes, so as to show the angular relation of the objects.

20 In carrying out our invention we provide an electric motor constituting a reproducer of angular movement and devices driven by the objects tending to produce magnetic fields in the rotor and stator elements of the reproducer displaced in accordance with the 25 positions of said objects. In one embodiment of our invention we make use of the so-called, "selsyn" generators or transmitting devices for transmitting in terms of rotation 30 the movements of the objects to the reproducing motor. The reproducing motor in one form of our invention has its rotor and stator elements provided with poly-circuit armature windings, which are electrically connected, respectively, to the selsyn generators 35 so that upon movement of the objects the rotor of the motor is caused to take up a position with relation to its stator which corresponds with the positional relation 40 of the objects.

For a better understanding of our invention reference should be had to the accompanying drawing in the single figure of which is shown in diagrammatic form a system 45 for reproducing relative angular motion embodying our invention.

Referring to the drawing, in this particular embodiment of our invention we have disclosed two indicators A and B which are 50 located adjacent two telescopes A' and B', respectively, remote from each other, and are actuated to show the relative angular positions of the telescopes. Indicators A and B are similar in construction. Each indicator 55 comprises two cooperating indicating dials,

one a coarse or slow speed dial and the other a fine or high speed dial. Indicator A is provided with a coarse dial 10 actuated at a 1:1 speed with the telescopes and with a fine dial 10' actuated at a suitable high 60 speed ratio with the telescopes, such as 72:1. Indicator B is provided with similar coarse and fine dials 11 and 11'. The fine or high speed dials are operated independently of their cooperating coarse or low speed dials. 65 They are used to make possible more accurate readings than can be taken on the coarse dials.

Dials 10 and 11 are driven by electric driving motors or reproducers 12 and 13, the 70 stator and rotor elements of which are connected, respectively, to selsyn generators or transmitting devices 14 and 15 shown as direct connected to the telescopes A' and B', respectively, so as to be driven in a 1:1 ratio 75 therewith. The selsyn generators 14 and 15 in one form of our invention are provided with single phase field windings 16 and 17 mounted on their rotor elements and with poly-circuit armature windings 18 and 19 80 mounted on their stator elements. Field windings 16 and 17 are electrically connected so as to be energized from a suitable source of alternating current supply 20. Armature windings 18 and 19 are both electrically connected 85 to reproducing motors 12 and 13.

The reproducing motors 12 and 13 are provided with poly-circuit armature windings 21 and 22 mounted on their rotor elements and with similar poly-circuit armature windings 23 and 24 mounted on their stator elements. These armature windings are shown as three-circuit delta-connected windings. Armature windings 23 and 24 are electrically connected through busses c, d, and e to armature winding 18 of selsyn generator 14, while armature windings 21 and 22 are electrically connected through busses f, g, and h to armature winding 19 of selsyn generator 15. On the driving shaft 25 of motor 12 is secured the dial 10 of indicator A. Cooperating with dial 10 is a stationary pointer 26. On the driving shaft 27 of motor 13 is secured the dial 11 of indicator B. Cooperating with dial 11 is a stationary pointer 28. The dials are suitably calibrated, such as in degrees and minutes of arc.

A similar system is provided for the actuation of high speed dials 10' and 11', which system will be understood with refer- 116

ence to the previous description, like parts being indicated by prime reference numerals. The generators 14' and 15' of the fine system, however, are driven by the telescopes A' and B', respectively, at a high speed 72:1 ratio therewith, generator 14' being driven by telescope A' through a pinion 30 meshing with a spur gear 31 secured to the telescope, and generator 15' being driven by telescope B' through a pinion 32 meshing with a spur gear 33 secured to the telescope.

As thus constructed and arranged, the operation of our invention is as follows: Voltages are induced by the alternating current field windings 16 and 17 of the selsyn generators 14 and 15 in the various legs of their respective cooperating armature windings 18 and 19, which voltages are impressed on the respective armature windings of motors 12 and 13 connected thereto. Alternating currents will flow in the rotor or stator windings or both of the motors 12 and 13 by virtue of the voltages impressed, and these currents will induce a resultant alternating single phase magnetic flux in the core of each motor, which flux will interlink with both rotor and stator windings and induce electromotive forces therein. If the rotor and stator be so angularly related that these induced electromotive forces oppose and equal as nearly as possible the voltages impressed, then the motor will be in equilibrium and without torque, and the total current input to the motor will be a minimum, but if the rotor be then turned through a small angle, the total current input will increase and a torque will develop tending to return the rotor to the said position of equilibrium. The rotors of the motors, being free, are thus turned until this relation of the windings is established.

Upon movement, for example, of telescope A' with relation to telescope B', which movement is transmitted to generator 14, the voltages induced in the legs of armature winding 18 are changed in value in such manner that they tend to cause an angular displacement of the fields of the motor windings 23 and 24 connected to armature winding 18. This results in a corresponding rotation of the motors 12 and 13 to re-establish a coincidence of magnetic fields, and hence the condition of equilibrium described above, whereby the relations of the rotor and stator elements of motors 12 and 13 are caused to correspond with the relation of the objects and dials 10 and 11 are turned to show the amount and direction of the movement given telescope A'. Movement of telescope B' to re-establish its positional relation with telescope A' tends to cause an angular displacement of the fields of motor windings 21 and 22 connected to its generator 15 in such direction that

the motors are caused to move dials 10 and

11 back to their former positions. Motors 12 and 13 are thus caused to be differentially responsive to movements of the telescopes, and consequently drive dials 10 and 11 so as to show the angular relation of the telescopes.

Simultaneously with the movement of the coarse dials, the fine dials 10' and 11' are operated to repeat the relative movements of the telescopes at their high speed ratio. By observing both coarse and fine dials, the positional relation of the telescopes can be determined with great accuracy.

When a zero point is chosen on the indicator corresponding to a predetermined relation, such as parallelism of the telescopes, the amount and direction of the angular displacement of the telescopes from this relation is indicated by the pointer. If a condition of parallelism is chosen, the indicator will always show the angle between the telescopes. It will be observed that if the telescopes are moved together in the same direction and in such manner that their original angular relation is not disturbed, the indicators will not be affected.

In the use of the telescopes A' and B' assuming that the telescopes are positioned not far from each other, should it be desired to designate a target toward which telescope A' is pointing to the operator of telescope B', it is only necessary for the operator of telescope B' to move his telescope until pointers 28 and 28' indicate on dials 11 and 11' a predetermined mark, such as the zero mark, corresponding to a condition of parallelism of the telescopes. The operator of telescope B' will then know that his line of sight is parallel to the line of sight of telescope A', and under usual conditions that he is pointing at the same target as the operator of telescope A'. The operator of telescope A' will likewise be advised of this condition by observing indicator A. Where the telescopes are located a considerable distance apart, however, it may be desirable to take into consideration the parallax angle between them.

Obviously our invention may be applied to objects given movement of translation. In such case the movements of translation of the objects must be converted and imparted to some object, such as a driving connection, in terms of rotation for the operation of our invention.

In accordance with the provisions of the patent statutes, we have described the principle of operation of our invention, together with the apparatus which we now consider to represent the best embodiment thereof, but we desire to have it understood that the apparatus shown is only illustrative and that the invention can be carried out by other means.

What we claim as new and desire to se-

cure by Letters Patent of the United States, is:

1. Means for reproducing relative motion comprising in combination with a plurality of independently movable objects, a reproducing device, inductively cooperating relatively movable polycircuit windings for said reproducing device, electrically inductive transmitting devices driven by said objects, polycircuit armature windings and single-phase alternating current fields for said transmitting devices, and electrical connections between the polycircuit windings of said reproducing device and the polycircuit windings of said transmitting devices respectively whereby magnetic fields are produced in the windings of said reproducing device, said fields varying in angular position in accordance with the angular positions of said objects.
  2. Means for reproducing relative motion comprising in combination with a plurality of independently movable objects, a reproducing device, inductively cooperating relatively movable polycircuit windings for said reproducing device, a plurality of transmitting devices driven by said objects respectively, field windings for said transmitting devices, a single-phase source of alternating current supply for said field windings, and electrical connections between the polycircuit windings of said reproducing device and the polycircuit windings of said transmitting devices respectively whereby fields are produced in the windings of said reproducing device varying angularly in accordance with the angular positions of said objects and the relation of said windings thereby caused to correspond with the angular relation of said objects.
  3. Means for reproducing angular motion comprising in combination with a plurality of independently movable objects, of an electric motor constituting a reproducing device, poly-circuit armature windings for the
- 50 55 60 65 70 75 80 85
- rotor and stator elements of said motor, transmitting devices driven by said objects, poly-circuit armature windings and field windings for said transmitting devices, a single-phase source of alternating current supply for said field windings, and electrical connections between the armature windings of said motor and the armature windings of said transmitting devices respectively whereby the relation of the rotor and stator elements of said motor is caused to correspond with the relation of said objects.
4. Means for differentially reproducing angular motion comprising in combination with a plurality of independently rotatable objects, a reproducing device provided with rotor and stator elements, three-circuit armature windings on the rotor and stator elements of said reproducing device, means for applying varying voltages to the circuits of said windings to cause the fields set up by said windings to rotate upon rotation of said objects, comprising two transmitting devices, driving connections between the rotor elements of said transmitting devices and said objects respectively, three-circuit armature windings on the stators of said transmitting devices, electrical connections between said armature windings and the windings of said reproducing device respectively, field windings on the rotor elements of said transmitting devices, and a single-phase source of alternating current supply for said field windings whereby voltages are induced thereby in the circuits of the respective co-operating armature windings and upon rotation of said field windings the value of said induced voltages is changed causing rotation of the field set up by the reproducer winding connected thereto.

In witness whereof, we have hereunto set our hands this 3rd day of January, 1922.

EDWARD M. HEWLETT.
WALDO W. WILLARD.
